UNITED STATES PATENT OFFICE.

CHARLES S. GOODING, OF BROOKLINE, AND THOMAS K. KEITH, OF BOSTON, MASSACHUSETTS, ASSIGNEES TO THE SEAVER SEWING-MACHINE COMPANY, OF MAINE.

BOOT OR SHOE SEWING-MACHINE.

SPECIFICATION forming part of Letters Patent No. 484,958, dated October 25, 1892.

Application filed November 20, 1891. Serial No. 412,515. (No model.)

To all whom it may concern:

Be it known that we, CHARLES S. GOODING, residing at Brookline, in the county of Norfolk, and THOMAS K. KEITH, residing at Boston, in the county of Suffolk, State of Massachusetts, have invented certain new and useful Improvements in Boot and Shoe Sewing-Machines, of which the following is a specification.

10 Our invention relates, chiefly, to that class of machines for sewing welts to the uppers and inner soles of boots and shoes in which a curved barbed needle is used in conjunction with a curved awl which moves in the same 15 path with the needle.

Our invention consists in the several improvements hereinafter described and claimed, relating to the presser-foot and lock-welt guide.

20 In this invention the shoe while being operated upon has the sole substantially vertical and the direction of feed is away from the operator. The shoe being so held and operated upon is much more easily controlled, the operator looking down at the work from the side 25 of the shoe upon which the work is being done.

In the accompanying drawings, forming a part of this specification, Figure 1 is a front elevation of the front part of the machine of 30 our invention. Fig. 2 is a side elevation of the same from the left of Fig. 1. Fig. 3 is a rear elevation. Fig. 4 is a plan of the front part of the machine. Fig. 5 is a section on line 5 5, Fig. 1. Fig. 6 is a detail elevation 35 of the needle rock-shaft connections. Fig. 7 is a detail elevation of the feed rock-shaft mechanism, looking from the left of Fig. 3. Fig. 8 is an elevation in detail of the awl-carrier connections. Fig. 9 is a similar view of 40 the needle-carrier and connections and the cast-off. Fig. 10 is an elevation, and Fig. 11 an elevation partly in section, of the cam-lever which actuates the feed rock-shaft. Fig. 11^a is a side elevation in detail of the needle 45 and cast-off. Fig. 11^b is a section on line 11 11, Fig. 11^a. Fig. 12 is a detail plan of the looper connection. Fig. 12^b is a vertical section on the axial line of the looper-rod. Fig. 13 illustrates a section of a boot with the nee-

dle-awl, &c., in their respective positions. 50 Fig. 14 is a section of the presser-foot lock on line 14 14, Fig. 1. Fig. 15 is a section of the same on line 15 15, Fig. 4. Fig. 16 is a side elevation of the presser-foot looper-needle and channel-gage, illustrating the operation of the 55 looper, the last and shoe being in section. Fig. 17 is a similar view showing the looper and needle in a different position. Fig. 18 is a horizontal section through the cast-off-rod 60 friction device.

In the drawings, *a* is the main shaft of the machine and turns in bearings *a'* *a'* in the frame *A*. The shaft *a* is rotated by the pulley *a*². The curved needle *b*¹⁷ is affixed to a carrier *b*¹⁶, mounted on a carrier-support *a*¹², 65 Fig. 2, which, as hereinafter described, is oscillated to give the needle lateral work-feeding movements by means of a rock-shaft *a*¹⁰, to which the carrier-support *a*¹² is affixed. The rock-shaft *a*¹⁰ is rocked by the following 70 mechanism: In the side of the pulley *a*² is a cam-groove *a*³, Fig. 7, which actuates the lever *a*⁴, said lever having a bearing *a*⁵ in the frame of the machine. A dovetail groove *a*⁶ in the lever *a*⁴ receives the adjustable 75 clamping-stud *a*⁷, Fig. 7. Said stud passes through a slot *a*⁸ in the arm *a*⁹, and may be clamped at any desired distance from the center of oscillation of the lever *a*⁴, thus providing for a variable throw of the arm *a*⁹ and 80 rock-shaft *a*¹⁰ from a fixed throw of the cam *a*³, for the purpose of varying the length of the stitches by varying the length of the movements of the needle-carrier support *a*¹². The arm *a*⁹ is fastened by set-screws to the 85 feed rock-shaft *a*¹⁰, said rock-shaft having bearings *a*¹¹ *a*¹¹ in the frame of the machine. To the opposite end of the rock-shaft *a*¹⁰ is fastened or otherwise secured the needle-carrier support *a*¹². The mechanism for oscillating the needle to cause it to alternately 90 enter and leave the work is as follows.

*b*² represents a lever, which is pivoted upon the stud *b*³ and is actuated by the stud *b*⁴, Figs. 2 and 6, on cam *b*, to which stud the 95 lever *b*² is connected by the link *b*⁴. The lever *b*² is provided with a slotted arm *b*⁵, to which is fastened the link *b*⁶ by the stud and nut *b*⁷.

Said link b^6 connects the lever b^2 to the arm b^8 , said arm being fastened to the needle-operating rock-shaft b^9 . Said needle rock-shaft has cast upon it the arm b^{10} , Fig. 2, which is connected by the link b^{11} to the sliding block b^{12} . The sliding block b^{12} is fastened by the stud b^{13} to the rod b^{14} , said rod b^{14} being adapted to slide in bearings in the needle-holder support a^{12} . The sliding block b^{12} is connected by the link b^{15} to the needle-holder b^{16} . The needle b^{17} is clamped to the needle-holder by a plate b^{18} and bolt b^{19} .

The needle-holder turns upon a stud b^{20} , screwed into the needle-carrier support a^{12} , and is provided with a flange b^{21} , which slides in a grooved segmental plate fastened to a^{12} , thus securing the needle-holder against lateral play.

c^9 , Figs. 5, 9, 11^a and 11^b, represents the cast-off, which is operated by the following mechanism: c , Figs. 2 and 3, represents a sliding rod, which has attached to it by set-screws the two blocks c^1 c^2 and is provided with means for holding it by friction in any position to which it may be moved by the sliding block b^{12} , which alternately raises and lowers it by striking the blocks c^1 c^2 , respectively.

The friction device referred to for holding the cast-off rod c in any position to which it may be moved by the block b^{12} is illustrated in Fig. 18, and consists of a leather plug or disk c^{10} , which is kept pressed against the rod c by the spring c^{11} and set-screw, c^{12} .

To the upper end of the rod c is attached the steel plate c^8 , Fig. 5, to which is fastened the stud c^4 , engaging the sliding block c^5 . Said sliding block actuates the forked arm c^6 , which is gripped to the shaft c^7 of the cast-off holder c^8 , Fig. 5. The cast-off c^9 is screwed to the cast-off holder, all as shown in Fig. 5. The needle is engaged by the cast-off to give it support, see Figs. 11^a and 11^b, the cast-off encircling about two-thirds of the circumference of the needle, the outer side of the needle or the part of the needle farthest from the center of rotation being left open, the object being to avoid striking the inner sole with the cast-off when the latter moves up to receive the loop thrown out by the needle.

d^{11} represents the awl, the operating mechanism of which is next described. The stud b' , Figs. 2 and 6, is connected to the arm d , Fig. 3, by the link d' . Said arm d is fastened to the awl rock-shaft d^2 , which turns in bearings d^3 d^8 on the frame A. To the other end of the awl rock-shaft is fastened the forked lever d^4 , which engages a sliding block upon a stud d^6 , fastened to the upright sliding rod d^7 . Upon the upper end of the sliding rod d^7 is secured a forked arm d^8 , Figs. 4 and 8, which is connected by the link d^9 to the awl-holder d^{10} , Fig. 8. The awl d^{11} is secured to the holder d^{10} by the cap d^{12} and screw d^{13} , Fig. 5. The awl-holder turns upon a stud d^{14} , which is screwed into the downwardly-projecting arm d^{15} , Fig. 5, of the frame A. e^6 represents the

presser-foot, which is arranged to bear on the work between the needle and welt-guide and is operated by the following mechanism:

The arm d^8 is provided with a boss e , Figs. 3 and 4, which receives a screw e' , the lower end of which bears against the end of a lever e^2 , Figs. 3 and 4, pivoted upon a stud e^3 on the frame A. The other end of the lever e^2 abuts against the casting e^4 , Figs. 2, 3, and 4, which is fastened to the upper end of the vertical sliding presser-foot rod e^6 . Said rod slides in bearings in the frame and has attached to its lower end the presser-foot e^6 . Said presser-foot is formed so as to pass over or bridge the needle b^{17} and rest upon the shoe at the right, as viewed in Fig. 2, of the point where the awl d^{11} punctures the stock. The presser-foot, in addition to the offset on foot proper e^{13} , which rests upon the welt w of the shoe, is provided with an arm or offset e^{14} , which rests upon the top of the welt-guide l , Fig. 2, when the presser-foot is depressed, thus holding the welt very firmly against the shoe in a position to be attached thereto by the thread, the offset e^{14} being arranged to bear on the welt at a point immediately over the channel-gage g , which supports the work against the downward pressure of the presser-foot. Hence the presser-foot, bearing directly on the welt at a point where the welt bears directly on the upper, presses the welt closely to place, and thereby relieves the stitch-forming mechanism and the thread of much of the strain that would otherwise be involved in drawing the welt closely to place. The presser-foot is kept down against the shoe by the spring e^7 , which bears upon the casting e^8 , attached to said presser-foot rod. The presser-foot is raised automatically by the lever e^2 to allow the shoe to be fed by the needle. The presser-foot is raised for the introduction of the work by the hand-lever e^9 , which is pivoted upon a stud e^{10} and abuts against the lower face of the casting e^{11} , fastened to the presser-foot rod. The presser-foot rod is prevented from rotating in its bearings by the casting e^8 , which embraces the looper-rod.

In order that the presser-foot may be held firmly against the shoe when the thread is being drawn up by the tension, and also when the needle is passing upward through the stock, we provide a presser-foot lock, which holds the presser-foot fixed, except when the shoe is being fed. We accomplish this by the following mechanism: The presser-foot rod e^6 is connected to the rod f' by the casting f^4 , Figs. 1, 2, 3, and 4. Said rod f' slides in bearings in the frame A and is kept down by the spiral spring f^2 , Fig. 1, bearing against the collar f^3 , attached to said rod f' . To the link d^9 , Fig. 1, is attached an adjustable collar f^6 , which as it is depressed engages the rod f^6 , Figs. 1, 14, and 15. Said rod passes through a hole in the pin f^7 , said pin turns in the hollow stud or sleeve f^8 , which is screwed into the frame A and is slotted to allow the rod f^6 to turn with the pin f^7 . The

pin f^7 projects beyond the stud f^8 into an opening in the frame and is made of a cam shape at f^9 , Fig. 15. A spring f^{10} , Fig. 1, keeps the cam f^9 normally pressed against the rod f' , thus locking it and the presser-foot rod and presser-foot to which it is connected. When the collar f^5 engages the pin f^6 , it overcomes the spring f^{10} , turning the pin f^7 and cam f^9 , so as to free the rod f' and leave the presser-foot free to be raised, in order that the shoe may be fed. The welt-guide consists of an arm l , Figs. 1 and 2, pivoted upon a screw l' on the arm d^{15} of the frame. The arm l is provided with an opening l^2 of substantially the shape of the welt after it is sewed to the shoe, and is prevented from falling down when not in use by the stop-pin l^3 , which is screwed into the arm l and notch l^4 , formed in the screw-head. The needle, cast-off, awl, and welt-guide turn about the same central axial line.

The looper i^8 , Figs. 16 and 17, is actuated as follows: A lever i , Fig. 3, pivoted on a stud i' , is actuated by the cam b . Said lever i is connected by the link i^2 to the arm i^3 , said arm i^3 is provided with a shank i^4 , Fig. 12, which fits in a hole drilled in the upright oscillating looper-shaft i^5 , and is fastened to said shaft by a vertical set-screw i^6 . The looper-shaft is prevented from endwise movement by the collars i^7 i^8 . To the lower end of the looper-shaft i^5 is attached the looper i^9 , consisting of a thread-eye i^{10} , Figs. 1, 16, and 17, formed upon the end of a small rod or wire, the shank of the wire being inserted in a hole in the end of the looper-shaft i^5 and in the center of said shaft. The thread passes through a thread-eye i^{10} , Figs. 3, 16, and 17, in the presser-foot bar e^5 , between the looper and the take-up. The looper is so timed, as illustrated in Figs. 16 and 17, that it draws thread from the take-up while the needle is drawing the loop through the stock and setting the previous stitch, so that when the needle comes up to take the thread from the looper there is slack thread between the needle and the take-up supplied by the looper, thus reducing the strain which would otherwise come upon the needle, as in the case when the needle draws its thread from the take-up direct.

The operation of the machine as a whole is as follows: The presser-foot e^6 is raised by means of the hand-lever e^9 , Fig. 2. The boot is then placed, as shown in Fig. 13, resting upon the channel-gage g . The presser-foot is then lowered until it bears upon the welt, forcing the welt firmly against the upper and inner sole. The shaft of the machine then

being rotated, the awl is forced downwardly through the stock and retreating is followed by the needle. The shoe is then fed forward to the left in Fig. 2 by the needle, which receives its motion through the rocking of the needle-carrier support a^{12} . The needle having fed the work, the looper i^9 passes the thread around the needle and into the barb of said needle, which descending draws the loop down with it, the looper returning to its former position to make way for the awl. The needle then moves to the right, Fig. 2, and, passing through the stock, throws out the loop, which is held by the cast-off while the needle receives a new loop, as described, which it draws through the loop previously formed, resulting in the ordinary chain-stitch with the chain or loop embedded in the channel. The thread passes from the looper to any suitable take-up and thence to the wax-pot.

We claim—

1. In a welt-sewing machine, the combination of the stitch-forming mechanism including an oscillating curved needle, a welt-guide arranged to guide the welt to the needle, a presser-foot arranged to bear directly on the welt between the welt-guide and needle at a point where the welt bears directly on the upper, and a channel-gage arranged to support the work against the downward pressure of the presser-foot, as set forth.

2. In a welt-sewing machine, the combination of the stitch-forming mechanism including an oscillating curved needle, a welt-guide arranged to guide the welt to the needle, and a presser-foot formed to bear on the welt between the needle and welt-guide and provided with an arm or offset formed to bear on the welt-guide, as set forth.

3. In a welt-sewing machine, the combination of the stitch-forming mechanism including an oscillating curved needle, a welt-guide arranged to guide the welt to the needle, a presser-foot formed to bear on the welt between the needle and welt-guide and provided with an arm or offset formed to bear on the welt-guide, and mechanism, substantially as described, for locking the presser-foot, as set forth.

In testimony whereof we have signed our names to this specification, in the presence of two subscribing witnesses, this 13th day of November, A. D. 1891.

CHARLES S. GOODING.
THOMAS K. KEITH.
